UNITED STATES PATENT OFFICE.

EDWARD F. O'DONNELL AND DANIEL ERICKSON, OF CHICAGO, ILLINOIS, ASSIGNEES,
BY MESNE ASSIGNMENTS, TO CRESCENT CHECK WRITER COMPANY, A CORPORATE
TION OF ILLINOIS.

CHECK-WRITING MACHINE.

1,358,458.

Specification of Letters Patent. Patented Nov. 9, 1920.

Application filed April 2, 1920. Serial No. 370,693.

To all whom it may concern:

Be it known that we, EDWARD F. O'DONNELL and DANIEL ERICKSON, citizens of the United States, and residents of Chicago, county of Cook, and State of Illinois, have jointly invented certain new and useful Improvements in Check-Writing Machines, of which the following is a specification, and which are illustrated in the accompanying drawings, forming a part thereof.

The invention relates to machines for filling in blank bank checks and like documents; and its object is to provide a simple and compact apparatus, the invention consisting particularly in the arrangement and support of the type characters, as will more fully hereinafter appear.

In the embodiment of the invention herein shown and described, it is applied in a machine for filling in the amount of the check, but it would, of course, be equally applicable for the printing of different characters.

In the accompanying drawings—

Figure 1 is an inverted plan view of the disk carrying the printing characters;

Fig. 2 is a bottom plan view of the machine, showing the arrangement of the operating levers;

Fig. 3 is a sectional view on the line 3—3 of Fig. 2, showing the machine in upright position; and

Fig. 4 is a face view of a check upon which the machine is operated.

The machine consists of a base 10, comprising a flat plate 11 and a depending flange or flanges, as 12, constituting supporting legs. This base, in the disclosed embodiment of the machine, is approximately square.

A frame 13, of the same general configuration, is mounted upon the base 10, and is rigidly secured thereto, and carries a cover plate 14 permanently fixed in place, upon which may be mounted an indicating disk 15 for guiding the operator in positioning the type characters for the printing operation.

A vertical spindle 16 is journaled centrally in the plates 11 and 14, and is provided at its upper end with a crank handle 17, by means of which it may be turned, and which also serves as a guide to the operator in connection with the indicating disk 15.

A circular disk 18 is fixed upon the spindle 16, and is positioned slightly above the plate 12 to permit the insertion of the sheet of paper upon which the printing is to be impressed, an aperture 19 in the body of the apparatus being provided to receive it. 60

A vertically reciprocable platen 20 is housed in a suitable slot in the plate 11, and may be forced upwardly against the lower face of the disk 18 by suitable levers, as 21, actuated by a crank shaft 22 journaled in 65 the flange or lugs 12, and provided with a crank arm 23 by means of which it may be rotated.

An abutment or backing block 24 depends from the plate 14 above the platen 20, its 70 lower end being contiguous to the upper face of the disk 18, this block serving to hold the disk against displacement by the upward pressure of the platen.

Suitable check feeding mechanism is provided, which need not be fully illustrated and described as it does not form a part of the present invention. It consists, however, of a pair of knurled wheels 25, 26, carried on a shaft 27 journaled in brackets secured 80 to the under face of the plate 11, and actuated by a pawl and ratchet mechanism 28 controlled by the lever 21 through a spindle 29.

An inking pad, semi-circular in form, is 85 supported in a carrier 30 mounted on or within the plate 11, suitable means being provided for forcing this pad upwardly against the under face of the disk. This mechanism is not herein described, as this 90 feature of the machine is not involved in the present invention.

The type characters are formed or secured to the under radial face of the disk 18, and are positioned adjacent its margin. Each 95 of these characters occupies a line 32 oblique to radii of the disk which intersects it, or, differently stated, on a line tangential to a circle concentric with but of smaller diameter than the disk. The various type 100 lines are uniformly spaced apart, adjacent lines subtending an acute angle. An annular zone 31 of the disk face, lying immediately within the zone occupied by the type characters, is adapted to be provided 105 with projections which will contribute to the perforation of the paper printed upon, these perforations aiding to cut or indent

the paper upon which has been written the name of the payee of the check with view to rendering changes in this name impossible. The position of a check or other slip 5 of paper 33, when being acted upon, is indicated in dotted lines on Fig. 2 and also the relation thereto of the lines 32 upon which the type characters are arranged and the zone 31. One line 32 is shown as in register 10 with the platen and this will be the line that will be impressed upon the check, and when so impressed is oblique to the printing line on the check.

Preferably the metal of which the type 15 characters and the zone 31 are formed is soft, and the type faces as well as the surface of the zone 31 are initially smooth. The face of the platen 20 is provided with numerous 20 projections, preferably in the form of points, and the length of the platen is such that it will coöperate with the zone 31 as well as with the type characters. The platen being 25 pressed upwardly against the disk, or, more properly, against the paper inserted between it and the disk, will perforate the paper and indent the faces of the type characters and a portion of the zone 31. Such 30 indentations will be formed in the soft metal carried by the disk upon each impression, unless the points of the platen shall enter the indentations previously made.

By the term "type character" as herein used is meant either a single letter or figure, a word, a fanciful design, or a symbol of 35 any nature which it may be desired to imprint or stamp upon the face of the check.

The details of the mechanism by which 40 ink is applied to the type characters, and for various other of the operations performed, not being claimed in this application, are not shown and described in detail.

In the operation of the machine as herein described, a check or similar slip of paper 45 33 having been inserted between the plate 11 and the disk 18 through the aperture 19, and having been engaged by the feeding wheels 25, 26, an impression by the platen against a line of the type characters will imprint such characters in and upon the surface of the 50 check, obliquely across a line longitudinal thereof, and will also cut the paper above this line by coöperation with the zone 31 of the disk. Upon the lowering of the platen the feeding wheels will be advanced a step, 55 carrying the check with them, and the next imprint upon the check will be on a line adjacent and parallel to the line previously printed. By this arrangement of the printing characters a phrase of considerable 60 length may be imprinted upon the face of the check and in type of sufficient size to be easily read, without rendering it neces-

sary to increase the length of the check beyond that which is commonly used.

We claim as our invention—

1. A check writer comprising, in combination, a circular disk, a series of groups of type characters on a radial face of said disk arranged to form words, said groups of type characters lying upon and adjacent one end of chords of the circle of equal length, such chords being equally spaced about the disk, means to ink said type, and means to press a check against selected of said groups with the printing line oblique to the chord upon 75 which a selected group lies while said check is being pressed thereagainst.

2. In a check writing machine, in combination, a rotatable disk bearing upon a radial face a plurality of lines of type characters, the several lines being arranged on equally spaced tangents to a common circle of less diameter than the periphery of the disk, a platen for coöperating with the type characters, means for compressing a check 80 between said platen and a selected one of said lines with the printing line of the check oblique to the selected line of type characters.

3. In a check writing machine, in combination, a disk bearing type characters upon a radial face and adjacent its periphery, and a set of perforating projections on such face and radially within the zone bearing the type characters, a platen for coöperating 95 with the type characters and the projections, and means for causing compressive engagement of the disk and platen.

4. In a check writing machine, in combination, a bed over which a check may be 100 moved in a right line, a platen acting through the bed with its longest dimension oblique to said right line, a revoluble disk mounted over the bed and bearing upon a radial face groups of type characters arranged in relatively oblique lines tangent to a circle concentric with and of smaller diameter than the disk, said groups being adapted to be brought successively and at will into alinement with said platen.

5. In a check writing machine, in combination, a disk bearing raised type characters on one radial face and on an annular zone adjacent the periphery of the disk, an annular zone immediately adjacent said type 11 zone raised on a level with the faces of said type characters, a reciprocable platen, means to cause a check to be compressed between said zones and platen, and a plurality of perforating projections on one of said 12 compressing means.

EDWARD F. O'DONNELL.
DANIEL ERICKSON.
